R. L. WRIGHT,

PROJECTILE

APPLICATION FILED JULY 29, 1919.

1,374,703.

Patented Apr. 12, 1921.

UNITED STATES PATENT OFFICE.

ROBERT LEE WRIGHT, OF LOS ANGELES, CALIFORNIA.

PROJECTILE

1,374,703.

Specification of Letters Patent. Patented Apr. 12, 1921.

Application filed July 29, 1919. Serial No. 314,165.

To all whom it may concern:

Be it known that I, ROBERT LEE WRIGHT, a citizen of the United States, and resident of Los Angeles, county of Los Angeles, and State of California, have invented certain new and useful Improvements in Projectiles; and I do hereby declare that the following is a full, clear, and exact description thereof.

10 This invention is a modified form of my inventions filed in the United States Patent Office and known by Serial Numbers as follows: Nos. 186,296, — 218,796, — 218,797, — 219,391, — 221,005, — 231,849, — 235,482, — 15 237,698,—and relates to shells and projectiles.

The particular object of this invention is to provide a shell pointer or projection having a removable percussion cap therein. Another object of my invention is to provide a shell pointer or projection having a channel for explosives therein.

The value and objects of my invention will be fully understood from the following description taken in connection with the drawing, which shows a longitudinal sectional view of my invention.

The figure shows an explosive projectile or shell 14 with a charge 3 therein, a slim shell pointer or projection 4 extending out of the point of the projectile or shell and 5 is a removable piece screwed onto the end of the shell pointer or projection. A firing pin is indicated at 6 in operative position to 30 explode the percussion cap 10, when said firing pin is struck. The firing pin is provided with a point the forward part of which is indicated at 7 and is normally held in inoperative position by the set screw 8 35 or other suitable means. The set screw may be removed when desired, thereby affording access to the firing pin.

The shell pointer or projection is provided with a channel or bore 11, as shown, in which any suitable explosive or charge may be placed. It will be noted that the part of the channel or bore which extends into the projectile is enlarged as at 13 in order that a greater quantity of explosive may be placed therein and also that the thickness of the shell pointer or projection around this part of channel or bore is reduced for an obvious purpose.

50 A light tube 18 is secured adjacent the rear of the shell pointer or projection for containing the explosive 17. A cap holder

10' for the primer cap is removably held in the shell pointer or projection as shown. If desired, this cap holder and cap may be removed and a solid blank piece inserted 60 in lieu thereof in order that the shell pointer or projection may be rendered safe for handling.

A removable plug is indicated at 12 being provided with a shoulder 21 against which the shell pointer abuts. The light tube 18 is held in place by threads 16 as shown. A plug is provided at 2 for the purpose of loading the projectile.

The operation of the device is as follows: 70 When the cap on the firing pin is struck, the firing pin is driven inward thereby exploding the cap 10. The explosives in channel or bore 11 are thereby ignited, which ignites the explosives 13, the latter causing the 75 charge 17 the the light tube 18 to be set off, thereby firing the main charge of explosive 3.

The device may be very readily manufactured, is sure of operation and is efficient. 80 If desired, for shipping or other purposes the shell pointer or projection may be removed by unscrewing it from the plug 12, after which a dummy plug may be inserted until it is desired that the projectile or shell 85 be used.

It is obvious that those skilled in the art may vary the details of construction as well as the arrangement of parts without departing from the spirit of the invention, and 90 therefore I do not wish to be limited to the above disclosure except as may be required by the claims.

What I claim as new and desire to secure by Letters Patent is:—

1. A projectile having a suitable cavity within to hold an explosive charge, a plug secured to one end of said projectile, a shell-pointer secured to said plug, said shell-pointer having an aperture therethrough, the 100 rear end of said aperture being enlarged and closed, a firing pin support removably secured in the forward part of said shell-pointer, a firing pin having an enlarged head arranged in advance of said support, a cap, 105 a set screw for holding the firing pin in inactive position and a tube for explosives surrounding the rear end of said shell-pointer.

2. A projectile having a suitable cavity 110 within to hold an explosive charge, a point formed thereon, a plug secured to said point,

a shell-pointer secured to said plug, said shell-pointer having a longitudinal aperture within, a firing pin support removably secured in the forward part of said shell-pointer, a firing pin secured in said support, means to hold the firing pin in position, a tube for explosives secured in the projectile adjacent to the cavity within the projectile surrounding the rear end of said shell-pointer, and a removable cap holder secured in the forward part of the aperture within the shell-pointer.

3. A projectile having a suitable cavity within to hold an explosive charge, a point thereon, an explosive charge within said cavity, a plug secured to said point, a shell-pointer secured to said plug, said shell-pointer having a longitudinal aperture, the rear end of said aperture being enlarged, an explosive charge within said aperture, a firing pin secured in the forward part of said shell-pointer, said firing pin having an enlarged head arranged in advance of a support, means to hold the firing pin in position, a tube for explosives adjacent to the explosive charge within the cavity of the projectile, surrounding the rear end of said shell-pointer, an explosive charge within said tube, a cap holder secured in the forward part of the aperture within the shell-pointer, a cap secured in said cap holder engageable by the firing pin secured in the forward end of the shell-pointer in a way to explode the cap and ignite the explosive charge within the aperture in said shell-pointer, ignite the explosive charge within the tube adjacent to the explosive charge within the projectile and ignite said explosive charge in the cavity within the projectile when the firing pin secured in the forward end of the shell-pointer comes in contact with the ground, object or target.

4. A projectile having a suitable cavity within to hold an explosive charge, an explosive charge within said cavity, a shell pointer secured to one end of said projectile, said shell-pointer having an aperture within, an explosive charge within said aperture, a movable firing pin removably secured in the forward part of said shell-pointer, means to hold said firing pin in position, a tube for an explosive charge adjacent to the explosive charge within the cavity of the projectile, an explosive charge within said tube surrounding the rear end of said shell-pointer, a removable cap holder mounted in the forward part of the aperture within the shell-pointer, a cap mounted in said cap holder and means to ignite the explosive charge within the aperture within the shell-pointer, ignite the explosive charge within the tube adjacent to the explosive charge in the cavity within the projectile, and ignite said explosive charge within the cavity of the projectile when the firing pin mounted in the forward end of the

shell-pointer comes in contact with the ground, object or target.

5. A projectile having a suitable cavity within to hold an explosive charge, a removable plug leading to said cavity, an explosive charge within said cavity, a driving band around the exterior of said projectile, a point formed on the forward end of said projectile with opening within said point, screw threads therein, a plug screwed into said opening, an opening in said plug, screw threads within said opening, a shell-pointer screwed into the opening of said plug, said shell-pointer having a longitudinal aperture within, the rear end of said aperture being enlarged, the walls and end made thinner, an explosive charge within said aperture, a movable firing pin removably secured in the forward part of said shell-pointer, means to hold the firing pin in position, a tube for explosives adjacent to the explosive charge within the projectile, screwed into the inner part of the threaded opening in the point of the projectile surrounding the rear end of said shell-pointer, an explosive charge within said tube, a removable cap holder secured within the forward part of the aperture within said shell-pointer, a cap secured in said cap holder, engageable by the firing pin secured in the forward end of the shell-pointer in a way to explode the cap and ignite the explosive charge within the aperture within the shell-pointer, ignite the explosive charge within the tube adjacent to the explosive charge in the cavity within the projectile and ignite said explosive charge within the cavity in the projectile when the firing pin secured in the forward end of the shell-pointer comes in contact with the ground, object or target.

6. An ordnance shell having a projection secured to the forward end thereof extending axially, and formed with a longitudinal bore in combination with a contact fuse having a detonating charge in alignment with the bore of said projection; and, at the rear end a similar detonating charge in operative relation to the booster charge of the shell, and communicating with and in alignment with the said passage.

7. An ordnance shell having a projection at the forward end thereof extending axially and formed with a longitudinal passage, in combination with a contact fuse having a detonating charge in operative relation to the forward end of said passage, and a second detonating charge at the rear end of said passage in operative relation to the explosive charge of the shell.

8. An ordnance shell having a projection at the forward end thereof formed with a longitudinal passage therethrough in combination with a contact fuse mounted on the forward end of said projection and having a detonating charge in operative relation to the

to the forward end of said passage; and a similar detonating charge in operative relation to the rear end of said passage and to the explosive charge of the shell.

5 9. An ordnance shell having a projection at the forward end thereof formed with a longitudinal passage therethrough, in combination with a contact fuse mounted on the forward end of said projection, and having a detonating charge in operative relation to the forward end of said passage; and a second detonating charge in operative relation to the rear end of said passage and to the explosive charge of the shell; the walls 10 of said projection, the passage therethrough, the contact fuse and the detonating charges being substantially symmetrical with respect to the axis of the shell and having their axes in alinement with each other and with 15 said axis of the shell so that the centrifugal forces due to axial rotation of the shell when it is fired, will be balanced in each cross-section of the device.

10. An ordnance shell having a projection 25 at the forward end thereof formed with a longitudinal passage therethrough, in combination with a contact fuse mounted on the forward end of said projection and having a detonating charge in operative relation to the forward end of said passage; and a second detonating charge in operative relation to the rear end of said passage and to the explosive charge of the shell, said projection being straight from the shell 30 35 to the forward end.

11. An ordnance shell having an explosive charge and means for detonating it, said means including an axially arranged tubular projection at the forward end of the shell, 40 a detonating charge in alinement with the rear of the passage through said projection and in operative relation to the explosive charge in the shell; and, in alinement with the forward end of said passage, another 45 detonating charge and means for detonating the latter including a contact firing pin, the total distance from the shell detonating charge to the forward contact surface of the firing pin being greater than the length 50 of the firing pin and the length of the firing pin covering only a practically negligible portion of said distance.

12. An ordnance shell having an explosive charge, a detonating charge in operative relation thereto and a contact fuse 55 having another detonating charge, and means including a short firing pin for detonating the latter, in combination with a tubular forward extension for the shell of 60 small diameter, light weight and considerable length as compared with the shell, said extension having said contact fuse secured at the forward end thereof and having a tubular cavity extending in a straight line from 65 the shell detonator to the fuse detonator,

the length of said passage being for the purpose and with the result of exploding the shell substantially in advance of the object which operates the firing pin.

13. An ordnance shell having an explosive charge and means for detonating it, said means including a tubular member, a detonating charge in alinement with the rear end of the passage through said tubular member and in operative relation to the explosive 70 charge of the shell; and, in alinement with the forward end of said passage, another detonating charge and means for detonating the latter including a contact firing pin, the length of said passage and the distance of 75 the fuse detonating charge in advance of the shell detonating charge being for the purpose and with the result of substantially advancing the position of explosion of the shell with reference to the object which 80 operates the firing pin.

14. An ordnance shell having a shell-pointer secured to the forward end thereof extending axially and a longitudinal bore formed within said shell-pointer, an explosive charge within said longitudinal bore, a cap and fuse secured in the forward part of said longitudinal bore and a contact firing pin with means to hold same in position 90 secured within the forward part of said shell-pointer in a way to explode said cap and ignite the explosive charge within the longitudinal bore within said shell-pointer when the contact firing pin comes in contact 95 with the ground, object or target.

15. An ordnance shell having a shell-pointer secured to the forward end thereof, extending axially and formed with a longitudinal bore for an explosive charge within 100 said shell-pointer, an explosive charge within said longitudinal bore and a contact firing pin and cap secured within said shell-pointer in a way that the contact firing pin 105 will explode said cap upon contact with the ground, object or target.

16. An ordnance shell having a shell-pointer secured to the forward end thereof, extending axially and formed with a longitudinal bore for an explosive charge within 110 said shell-pointer, the rear end of said longitudinal bore being larger in circumference, and the walls and end of shell-pointer made thinner to cause same to explode at said rear end of shell-pointer, a tube for explosives secured within the shell incasing the 115 said rear end of the shell-pointer, an explosive charge within said tube, a cavity for explosives within said shell, said cavity incasing said tube, an explosive charge within 120 said cavity and a contact firing pin and cap secured in the forward part of said shell-pointer, means secured within said shell-pointer to ignite the explosive charge within 125 said longitudinal bore within said shell-pointer and means to ignite the explosive 130

- charges within the said tube and shell with the fire and force of the explosion of the explosive charge within the bore of said shell-pointer.
- 5 17. An ordnance shell having a shell-pointer secured to the forward end thereof, extending axially and formed with a longitudinal bore for an explosive charge within said shell-pointer, an explosive charge within 70 said longitudinal bore, a contact firing pin and cap secured within the forward part of said shell-pointer, a tube for explosives secured within said shell incasing the rear end of said shell-pointer, an explosive charge 75 within said tube, a cavity for explosives within said shell incasing said tube, an explosive charge within said cavity, means to ignite the explosive charge within the longitudinal bore within said shell-pointer and 80 means to ignite a plurality of explosive charges secured within said shell with the fire and force of each explosive charge exploded in advance of each other. 85
18. An ordnance shell having a shell-pointer secured to the forward end thereof, extending axially and formed with a longitudinal bore for explosives within said shell-pointer, an explosive charge within said longitudinal bore, a cavity for explosives 90 within said shell and means secured within said shell-pointer to ignite the said explosive charges within said shell-pointer and said shell. 95
19. An ordnance shell having a removable shell-pointer secured to the forward end thereof extending axially and formed with a longitudinal bore for explosives within said shell-pointer, an explosive charge within said longitudinal bore, a contact firing pin and cap secured within the forward part of said shell-pointer, a cavity for explosives within said shell, an explosive charge within said cavity and means secured within said shell-pointer to ignite said 105 explosive charge within the cavity of said shell. 110
20. An ordnance shell having a shell-pointer secured to the forward end thereof extending axially and formed with an explosive charge within said shell-pointer, a cap secured within said shell-pointer, an explosive charge secured within said shell and means secured within said shell-pointer to ignite the explosive charge within said shell-pointer and ignite the explosive charge within said shell. 115
21. An ordnance shell having a shell-pointer secured to the forward end thereof extending axially and formed with an explosive charge within said shell-pointer, a cap and fuse secured within said shell-pointer, a plurality of explosive charges secured within said shell and means secured within said shell-pointer to ignite the explosive charge within said shell-pointer and 120
- 60 65 125 130

extending axially, a plurality of explosive charges secured within said shell-pointer and means secured within said shell-pointer to ignite said plurality of explosive charges 5 within said shell-pointer.

29. An ordnance shell having a shell-pointer secured to the forward end thereof extending axially, an explosive charge and cap secured within said shell-pointer and 10 means secured within said shell-pointer to ignite said explosive charge within said shell-pointer, said shell-pointer being straight from the shell to the forward end and the outer part having its walls of material and thickness sufficient to confine the 15

force of the explosion against material lateral expansion.

30. An ordnance shell having a shell-pointer composed of a plurality of parts secured to the forward end thereof extending 20 axially, an explosive charge secured within said shell-pointer and means secured within said shell-pointer to ignite said explosive charge within said shell-pointer.

In testimony whereof, I have hereunto set 25 my hand in the presence of two witnesses.

ROBERT LEE WRIGHT.
